John Fahnestock -

United States Patent Office.

JOHN FAHNESTOCK, OF ASTORIA, NEW YORK, ASSIGNOR TO B. E. BARKER,
OF INDIANAPOLIS, INDIANA.

Design No. 3,010, dated May 5, 1868.

DESIGN FOR A TRADE-MARK.

The Schedule referred to in these Letters Patent and making part of the same.

TO ALL WHOM IT MAY CONCERN:

Be it known that I, JOHN FAHNESTOCK, of Astoria, in the county of Queens, and State of New York, have invented a new and useful Design for Tobacco-Labels; and I do hereby declare that the following is a full, clear, and exact description of the same, reference being had to the accompanying drawings, making a portion of this specification, and representing a tobacco-label made according to my design.

The central part of the label is surrounded by an outer annular border, A, the inner and outer peripheries of which are described by broad lines, *a b*, between which and the colored middle part, *c*, are plain spaces, *d*. The lower part of the inner side or edge of the border A, instead of being on a curve continuous with the upper part of such edge, is somewhat elevated toward the centre of the design, as shown at *a**. The central and upper portion of the border A has formed therein, in fancy capital letters, the words "Highland Gem," and that portion of such border below the upwardly-extended part, *a**, of the inner circumference thereof, has formed in it, in similar letters, the words "B. E. Barker," below which, in smaller letters of like character, is the word "Indianapolis." The central portion, B, of the design, within the border A, just hereinbefore described, is occupied by a landscape view, the background of which represents a hilly prospect, as indicated at *e*, and in the foreground of which is seated a human figure, *B**, dressed in what is termed the Highland costume, wearing a cap, *f*, with a feather, *a'*, and holding in its left hand a smoking-pipe, *g*. At the right side of the figure just mentioned is shown a bush, *C**, and at the opposite side of such figure is the figure, *D**, of a dog, in a sitting position, and apparently gazing at the human figure, *B**. Beyond the figure *D** of the dog, toward the adjacent edge of the design, is indicated a rock, *E*, back of which is a bush, *F*.

What I claim as my invention, and desire to secure by Letters Patent, is—

The design for a tobacco-label, substantially as herein described and shown.

JOHN FAHNESTOCK.
